A. M. STOKOE.

APPARATUS FOR SORTING CLOTHING AND OTHER ARTICLES.

APPLICATION FILED DEC. 16, 1919.

1,388,385.

Patented Aug. 23, 1921.

UNITED STATES PATENT OFFICE.

ASHLEY M. STOKOE, OF ST. PAUL, MINNESOTA.

APPARATUS FOR SORTING CLOTHING AND OTHER ARTICLES.

1,388,385.

Specification of Letters Patent. Patented Aug. 23, 1921.

Application filed December 16, 1919. Serial No. 345,433.

To all whom it may concern:

Be it known that I, ASHLEY M. STOKOE, a citizen of the United States, residing at St. Paul, in the county of Ramsey and State of Minnesota, have invented a new and useful Apparatus for Sorting Clothing and other Articles, of which the following is a specification.

My invention relates to improvements in apparatus for sorting clothing and other articles.

In what is called rough-dry work, laundries commonly employ similarly numbered pins of the safety-pin type, to identify the pieces of a certain customer. When the work is received at the laundry, a number is assigned to the owner. Pins bearing this number are taken from a tray similarly numbered and placed in the garments or pieces of the patron. Articles belonging to numerous patrons are intermingled as they pass through the washing machines and driers. It is necessary, therefore, to thereafter separate the laundried pieces. In common practice, the intermingled articles are taken to a sorting room in which arms or brackets are arranged. Each bracket is numbered and the sorter is intended to hang all articles bearing the same number, upon said bracket. The contents of each bracket comprises the work for an individual and the fact that articles are found on said bracket is sufficient reason, without further investigation, for an attendant to wrap and mark the same for delivery to the patron to which the number on said bracket has been assigned. The pins are, of course, removed from the articles and replaced in the trays. Errors often occur in distributing the pieces. A garment bearing one number inadvertently placed upon a bracket bearing a different number results in a shortage to one of the patrons. The pins from each rack are placed in a tray, the fact that said pins are on a certain rack being sufficient reason for placing all of them in said tray. A misplaced pin, causing an error in the sorting room, results in repetition of the error until discovered and said misplaced pin located and returned to the proper group of pins bearing its number.

It is the object of my invention to provide markers for clothing and racks and trays to receive the markers, certain markers being capable of application, only, to certain racks and trays.

A further object is to provide an apparatus including such markers, racks and trays, all of which are simple, durable and inexpensive in construction, said markers being readily applicable to their corresponding racks and trays.

With the foregoing and other objects in view, which will appear in the following description, the invention resides in the novel combination and arrangement of parts and in the details of construction hereinafter described and claimed.

In the drawings, Figure 1 is a perspective view illustrating a rack with a marker applied thereto and shows in dotted lines, a garment suspended from said marker; Fig. 2 is a perspective view of a tray showing a marker in position thereon; Figs. 3 and 4 are side views of a marker, the latter being shown in position upon a rack, which appears in cross-section and Fig. 5 is an end view of said marker.

Referring to the drawing, I have used the reference letter A to indicate a rack, B to indicate a tray and C to designate a marker, which may be placed upon said tray or applied to the rack, as shown. The rack A comprises a flange 10 adapted to be fixed to a wall or other support and a rack-bar 11 detachably mounted in said flange and projecting horizontally or substantially so from the support. The flange 10 bears a number *a* or other identifying symbol. The rack-bar 11, as shown, is formed with ways 12 therein, the outer end of said bar being beveled or tapered as at 13. The invention contemplates the use of a plurality of such bars 11, each bar having a cross-sectional contour differing from that of each of the other bars. The ways 12, therefore, may vary in form, number and arrangement.

The tray B comprises a base 14 furnished with an upright post 15 formed with ways 12^a and a tapered tip 13^a, as in the bar 11. A section through this post is identical with a similar section through the bar 11. My apparatus includes a plurality of trays B equal in number to that of the racks A, each tray bearing a number *b* or other designating symbol like that of the rack, whose bar 11 corresponds with the post 15 of said tray.

The marker C includes an oblong sheet metal body 16 and a spring wire 17, which is bent as in the usual safety pin. The margin 18 of said body is turned over one member 17^a of the wire 17 and clamps the same

in place thereon. A medial section is cut from the opposite margin of the body leaving a head 19 above the notch, so formed, and a bar 20 therebeneath. The head 19 is 5 turned upon itself to form a combination clasp and guard 21 for the pointed tip of the free member 17^b of said wire 17 and the end of said bar 20 is turned slightly to form a second clasp 22 for said free member at 10 the base of the body 16. Said member 17^b is released from the clasps 21 and 22 to permit the same to be pinned to an article or removed therefrom and is thereafter returned to position within the grasp of said clasps. 15 This member of the wire obstructs the open side of the notch in the body 16 and completes an aperture 23, which receives the rack-bar 11 and post 15. Wards 24 projecting from the body fit in the ways 12 and 12^a 20 in said bar and post. Wards of various numbers, shapes and arrangement are formed in the bodies of various markers to fit in corresponding ways of the various racks and trays. Upon the head of the marker C is 25 placed a numeral *c* or other symbol corresponding with the symbol on its companion rack and tray.

The supply of markers C, bearing a certain number, are kept, one upon the other, 30 on the post 15 of a tray B similarly numbered. A graduated scale 25 on said post shows at a glance the quantity of markers on hand. A marker is pinned to each piece of a bundle to be laundried. When laundried and in being sorted from articles bearing other numbers, said pieces are hung upon a rack A bearing the number corresponding with the markers thereon. They cannot be hung on any other rack, because the wards 35 24 on the bodies of the markers will not so permit. When the sorting is completed, the contents of a rack is wrapped and directed for delivery to the patron to whom the rack number had been assigned, the markers A 40 45 being first removed from the pieces. Said markers are then returned to their proper trays and there can be no error in this, because the wards 24 in the bodies of said markers will fit, only upon the post of a

tray correspondingly designed and numbered. It will, therefore, be seen that when the pins from a tray are again used to identify the pieces of a certain patron, no errors can arise by marking some of said pieces with one number and others with another 55 number or numbers.

Changes in the specific form of my invention, as herein disclosed, may be made within the scope of what is claimed without departing from the spirit of my invention. 60

What I claim as new and desire to protect by Letters Patent is:

1. In a device of the class described, a rack and a marker adapted to be applied to said rack, said marker comprising a body, 65 a yielding pin thereon, a guard on the body and a clasp thereon spaced apart from said guard, both guard and clasp being adapted to embrace said pin, said body having an aperture between said guard and clasp designed to conform with and receive the rack. 2. In a device of the class described, a rack, a marker adapted to be applied to and supported by the rack, said marker comprising a body and a pin adapted to be caught 75 in an article of clothing or the like and having a yielding member, clasps on the body to secure said yielding member, said body having a notch therein to receive the rack, said yielding member being adapted to obstruct 80 the open side of said notch and secure the marker upon said rack, said notch being designed to conform with and fit the rack.

3. In a device of the class described, an upright post, a portable base therefor, markers adapted to be supported by the base and arranged to be held, one upon the other, by said post, over which said markers may be freely passed, a graduated scale on said post to indicate the number of markers thereon, 85 each marker including means for attaching the same to an article of clothing and designed to prevent its application to another post of different design. 90

In testimony wherof, I have signed my 95 name to this specification.

ASHLEY M. STOKOE.
